US00D873502S

(12) **United States Design Patent** (10) Patent No.: **US D873,502 S**
MacNeil et al. (45) Date of Patent: ** Jan. 21, 2020

(54) **DOUBLE BOWL LOW-PROFILE PET FEEDING STATION**

(71) Applicant: **MacNeil IP LLC**, Bolingbrook, IL (US)

(72) Inventors: **David F. MacNeil**, Fort Lauderdale, FL (US); **Frederick W. Masanek, Jr.**, Barrington, IL (US)

(73) Assignee: **MACNEIL IP LLC**, Bolingbrook, IL (US)

(**) Term: **15 Years**

(21) Appl. No.: **29/653,512**

(22) Filed: **Jun. 15, 2018**

Related U.S. Application Data

(63) Continuation-in-part of application No. 29/635,541, filed on Jan. 31, 2018, which is a continuation-in-part of application No. 29/621,052, filed on Oct. 4, 2017, which is a continuation-in-part of application No. 29/602,916, filed on May 4, 2017, which is a continuation-in-part of application No. 29/560,208, filed on Apr. 4, 2016, now Pat. No. Des. 802,853.

CLAIM

We claim the ornamental design for a double bowl low-profile pet feeding station, as shown and described.

DESCRIPTION

FIG. 1 is a top perspective view of a first embodiment of a double bowl low-profile pet feeding station according to our design;

FIG. 2 is a top perspective view of the embodiment shown in FIG. 1, in which the bowls are shown raised out of the combined mat and stand component;

FIG. 3 is a bottom perspective view thereof;

FIG. 4 is a top view of the embodiment shown in FIG. 1;

FIG. 5 is a front view of the embodiment shown in FIG. 1;

FIG. 6 is a rear view of the embodiment shown in FIG. 1;

FIG. 7 is a right side view of the embodiment shown in FIG. 1, a left side view thereof being a mirror image of the right side view;

FIG. 8 is a top perspective view of the combined mat and stand component used in the embodiment shown in FIG. 1;

FIG. 9 is a top view thereof;

FIG. 10 is a front view thereof;

FIG. 11 is a rear view thereof;

FIG. 12 is a right side view of the combined mat and stand component shown in FIG. 8, a left side view thereof being a mirror image of the right side view;

FIG. 13 is a transverse sectional view taken along line 13-13 of FIG. 9;

FIG. 14 is a longitudinal sectional view taken along line 14-14 of FIG. 9;

FIG. 15 is a top perspective view of the double bowl low-profile pet feeding station according to a second embodiment;

FIG. 16 is a top perspective view of the embodiment shown in FIG. 15, in which the bowls are shown raised out of the combined mat and stand component;

FIG. 17 is a bottom perspective view thereof;

FIG. 18 is a top view thereof;

FIG. 19 is a front view thereof;

FIG. 20 is a rear view thereof;

FIG. 21 is a right side view of the embodiment shown in FIG. 15, a left side view thereof being a mirror image of the right side view;

FIG. 22 is a top perspective view of the combined mat and stand component used in the embodiment shown in FIG. 15;

FIG. 23 is a top view thereof;

FIG. 24 is a front view thereof;

FIG. 25 is a rear view thereof;

FIG. 26 is a right side view of the combined mat and stand component shown in FIG. 22, a left side view thereof being a mirror image of the right side view;

FIG. 27 is a transverse sectional view taken along line 27-27 of FIG. 23;

FIG. 28 is a longitudinal sectional view taken along line 28-28 of FIG. 23;

FIG. 29 is a top perspective view of the double bowl low-profile pet feeding station according to a third embodiment;

FIG. 30 is a top perspective view of the embodiment shown in FIG. 29, in which the bowls are shown raised out of the combined mat and stand component;

FIG. 31 is a bottom perspective view thereof;

FIG. 32 is a top view thereof;

FIG. 33 is a front view thereof;

FIG. 34 is a rear view thereof;

FIG. 35 is a right side view of the embodiment shown in FIG. 29, a left side view thereof being a mirror image of the right side view;

FIG. 36 is a top perspective view of the combined mat and stand component used in the embodiment shown in FIG. 29;

FIG. 37 is a top view thereof;

FIG. 38 is a front view thereof;

FIG. 39 is a rear view thereof;

FIG. 40 is a right side view of the combined mat and stand component shown in FIG. 36, a left side view thereof being a mirror image of the right side view;

FIG. 41 is a transverse sectional view taken along line 41-41 of FIG. 37;

FIG. 42 is a longitudinal sectional view taken along line 42-42 of FIG. 37;

FIG. 43 is a top perspective view of the double bowl low-profile pet feeding station according to a fourth embodiment;

FIG. 44 is a top perspective view of the embodiment shown in FIG. 43, in which the bowls are shown raised out of the combined mat and stand component;

FIG. 45 is a bottom perspective view thereof;

FIG. 46 is a top view thereof;
FIG. 47 is a front view thereof;
FIG. 48 is a rear view thereof;
FIG. 49 is a right side view of the embodiment shown in FIG. 43, a left side view thereof being a mirror image of the right side view;
FIG. 50 is a top perspective view of the combined mat and stand component used in the embodiment shown in FIG. 43;
FIG. 51 is a top view thereof;
FIG. 52 is a front view thereof;
FIG. 53 is a rear view thereof;
FIG. 54 is a right side view of the combined mat and stand component shown in FIG. 50, a left side view thereof being a mirror image of the right side view;
FIG. 55 is a transverse sectional view taken along line 55-55 of FIG. 51;
FIG. 56 is a longitudinal sectional view taken along line 56-56 of FIG. 51;
FIG. 57 is a top perspective view of the double bowl low-profile pet feeding station according to a fifth embodiment;
FIG. 58 is a top perspective view of the embodiment shown in FIG. 57, in which the bowls are shown raised out of the combined mat and stand component;
FIG. 59 is a bottom perspective view thereof;

FIG. 60 is a top view thereof;
FIG. 61 is a front view thereof;
FIG. 62 is a rear view thereof;
FIG. 63 is a right side view of the embodiment shown in FIG. 57, a left side view thereof being a mirror image of the right side view;
FIG. 64 is a top perspective view of the combined mat and stand component used in the embodiment shown in FIG. 57;
FIG. 65 is a top view thereof;
FIG. 66 is a front view thereof;
FIG. 67 is a rear view thereof;
FIG. 68 is a right side view of the combined mat and stand component shown in FIG. 64, a left side view thereof being a mirror image of the right side view;
FIG. 69 is a transverse sectional view taken along line 69-69 of FIG. 65; and,
FIG. 70 is a longitudinal sectional view taken along line 70-70 of FIG. 65.
In each of the embodiments, the bottom of the combined mat and stand component is unadorned and forms no part of the design claim. The broken line showing of the underside surface of the combined mat and stand component of the feeding station depicts unclaimed portions that form no part of the design claim but are shown for illustrative purposes.
